UNITED STATES PATENT OFFICE.

LEVI L. FUNK, OF CHICAGO, ILLINOIS.

CAP FOR RECEPTACLES.

Application filed August 18, 1928. Serial No. 300,601.

This invention relates to a cap for closing receptacles, as say, bottles, flexible tubes, and the like.

Among the objects of the invention is to obtain a screw threaded cap which fits corresponding screw threads on the neck of a receptacle and by means of which a small quantity of fluid or plastic material may be made to flow from the receptacle, without removing 10 the cap from said neck.

In the drawing which illustrates a cap embodying the invention, Fig. 1 is an elevation of the upper end and neck of a receptacle, with a cap also shown in elevation on said 15 neck.

Fig. 2 is a top plan view of the cap which is illustrated in Fig. 1; and

Fig. 3 is a vertical section of the neck of a receptacle and a cap embodying the invention thereon, taken on line 3—3 of Fig. 2, viewed as indicated by arrows.

A reference character applied to designate a given part indicates said part throughout the several figures of the drawing, wherever 25 the same appears.

1 illustrates the upper end of a receptacle, and 2 the neck thereof. 3 illustrates the ordinary screw threads on neck 2, where a screw threaded cap is applied as a closure. 4 represents a cap which is provided with screw threads 5 on the cylindrical part thereof, fitting on screw threads 3. 6, 7 respectively represent apertures in the cylindrical part of cap 1, adjacent to the substantially flat end of 30 the cap. 8 and 9 represent lips which are forced out from the cylindrical part of cap 1, in making apertures 6, 7, respectively. 10 represents a lip substantially like lips 8, 9, which is also forced out from the cylindrical 35 part of cap 1, leaving an aperture substantially like apertures 6, 7. Lip 10 in place of being forced outwardly, as are lips 8, 9, is forced inwardly, for a purpose about to be described. A plurality of lips 10 may be forced inwardly 40 from the cylindrical part of cap 1, if preferred, in the same way a plurality of lips 8, 9, are obtained. 11 represents a disk preferably made of leather or other suitable material, as fabric. 12 represents a disk, which 45 is preferably made of soft or ductile metal.

When disk 12 is forced down on to the upper edge of the neck of the receptacle discharge of liquid or semi-liquid from the neck 50 is prevented, the neck being thereby tightly

closed; and when the cap is turned to loosen it from the neck, disk 12 being loosened from the neck by lip 10, liquid will flow from the aperture 6, or 7, the receptacle being properly tilted. If the receptacle be a tube of ductile metal, and the cap be loosened by turning it slightly on the neck thereof, semi liquid contents of the receptacle can be forced from the receptacle through apertures 6, 7, or one thereof if there be but one, by pressure on the tube, or other receptacle.

The purpose of lip or lips 10 is to loosen disk 12 from the upper end or edge of the neck of the receptacle when the cap is loosened therefrom by a partial turn thereof on said neck, and for this purpose the tip or end of 65 the lip is positioned underneath the disk, near the periphery thereof.

Where disks 11, 12, or one thereof, are not placed in cap 4 the lip or lips 10 are not required, and when said disks or either one 75 thereof are placed in said cap lip or lips 10 may be substituted for lip 9, as in that case air may flow into the receptacle through the aperture which is made by forcing the lip 10, or lips 10, out of the cylindrical part of the 80 cap, to replace the liquid flowing from the receptacle, when the receptacle is tilted, as described.

Also, when the receptacle is made of ductile metal and is filled with a semi-liquid mass 85 such semi-liquid may be forced from the aperture or apertures made by forcing lips 10 out from the cylindrical part of the cap; and in this case a plurality of lips 10 may be substituted for lips 8 and 9, if preferred.

I claim:

1. A cap provided with a screw threaded cylindrical part adapted to fit on a correspondingly screw threaded neck of a receptacle, a disk in said cap, said cylindrical part provided with apertures and lips to said apertures, one of said lips adapted to hold said disk in a determined position in said cap, and one thereof adapted to form a spout to one of said apertures, all in combination.

2. A cap provided with a screw threaded cylindrical part adapted to fit on a correspondingly screw threaded neck of a receptacle, in combination with a disk in said cap, said cylindrical part provided with a lip extending inwardly and adapted to hold said disk in a determined position in said cap.

LEVI L. FUNK,
